UNITED STATES PATENT OFFICE.

JOHN WILLIAM FRIES, OF WINSTON SALEM, NORTH CAROLINA.

APPARATUS FOR HUMIDIFYING AND CLEANSING AIR.

No. 831,275.

Specification of Letters Patent.

Patented Sept. 18, 1906.

Application filed April 24, 1902. Serial No. 104,481.

To all whom it may concern:

Be it known that I, JOHN WILLIAM FRIES, of Winston Salem, county of Forsyth, State of North Carolina, have invented an Improvement in Apparatus for Humidifying and Cleansing Air, of which the following is a specification.

My invention has reference to apparatus for humidifying and cleansing air; and it consists of certain improvements fully set out in the following specification and shown in the accompanying drawings, which form a part thereof.

The object of my invention may be said to be twofold—namely, to regulate the humidity of the air within any confined space, such as a large room or auditorium, and to collect and remove all dust and floating particles of dirt or deleterious matters from the air, thereby purifying and refreshing it.

In many instances it is important to add moisture to an otherwise dry atmosphere to increase the humidity, whether it be for facilitating manufacturing operations or for hygienic reasons and comfort. Thus, for instance, in textile mills when the atmosphere is too dry—*i. e.*, its hygrometric condition too low in humidity—the cotton becomes under the ordinary manipulations electrified, with the result that the fiber ends stand out and give to it a more or less fuzzy appearance. This condition interferes materially in the textile operations of producing cloth. By my invention the humidity may be increased to the proper degree to secure such hygrometric conditions as will overcome this abnormal tendency of the yarn to become electrified.

In many mills the atmosphere becomes so heavily laden with floating particles of dust that, aside from being dangerous on account of fire, it is most objectionable and injurious to the workmen and girls employed in operating the machines. By my invention all of the objectionable floating particles may be extracted from the air and the latter brought to a fresh and healthful condition.

In carrying out my invention I provide means to act upon air and a spray of water, whereby the air carries the water in suspension to a circulating device, which imparts to it a centrifugal and rotary action for the purpose of spreading the water out upon the interior surface of a cylindrical shell for causing the air to take a spiral path over the surface of said film of water for the purpose of be-

coming humidified to the proper degree. When this is done, the air and water are caused to pass into a discharge-flue, which collects the surplus water and removes it and also separates the humidified air and directs it into the room. This same operation purifies the air, because the action of the moisture is such that it causes the floating particles to separate from the air and become absorbed by the water and by which they are conveyed away. It is thus seen that the humidified air is not only of the right condition for the proper working of the cotton, but it is washed or cleansed and brought to a condition most healthful and pleasant to the operatives. It is evident that these same conditions are most desirable in large halls and auditoriums or places where people may congregate, and hence my invention is adapted to such purpose.

In my preferred form of apparatus for carrying my invention into effect I employ a tube, into which air and a spray of water are sucked, combined with a second tube or shell upon which the water collects in a film and over which the air is forced, a circulating-fan connecting the tube and shell for creating a forced circulation of the air and moisture and imparting to them an outward and rotary motion within the shell, and means for collecting and removing the water and for delivering the air in humidified condition into the room exterior to the apparatus. I have found it convenient and more compact to inclose the tube within the shell, so that the air and moisture drawn through the central tube is caused to flow backward through the annular chamber within the outer and inclosing shell and between it and the tube.

My invention also embodies details of construction, which, together with the above general features, will be better understood by reference to the drawings, in which—

Figure 1 is a sectional elevation of an apparatus embodying my invention. Fig. 2 is a cross-section of same on line 2 2 of Fig. 1. Fig. 3 is an end elevation of same with the discharge-flue removed. Fig. 4 is a cross-section of the discharge-flue on line 4 4 of Fig. 1, and Fig. 5 is a sectional elevation of a modified form of apparatus embodying my invention.

A is a hollow cast-iron head and is closed at the front and open at the rear, where it is provided with a rearwardly-extending circular flange B. This hollow cast head is made

in shape very similar to a centrifugal blower-casing, its periphery being spiral in shape tangentially considered and opening downwardly through a discharge-opening at C, 5 preferably rectangular in form and located to one side of the head. Fitted to the flange B is a cylindrical shell D, of sheet metal, the opposite end thereof being closed by a cast-metal cap E, flanged, as at e, to receive the 10 end of the said sheet-metal shell D. Arranged concentrically within the shell D is a tube F, secured at one end to an annular ring G⁴, which is bolted to the front of the head A, and terminating at the other end near the 15 cap E, but at sufficient distance therefrom to allow of the interposition of a circulating-fan G. This fan is so designed that it draws in the air from the tube F and discharges it radially and tangentially under centrifugal action, as shown. The fan consists of a closed 20 back g and a series of radial blades J, extending forward from the back. These blades are connected at the front part by an annular ring-piece H, which is in alinement with the 25 end of the tube F. The apertures or passages formed between the blades J near the hub of the fan are curved, as at I. This fan is rotated by a shaft K, journaled in a suitable frame L and driven by a band-wheel M, 30 or, if desired, by any of the well-known means for driving fans now in commercial use—such, for example, as the direct application of an electric motor. The frame L is bolted to the cap E and is adapted for attachment to 35 the ceiling or other convenient place. The head A is also provided with a support L', likewise adapted for attachment to the ceiling. By means of these frames L' and L the entire apparatus may be suspended in suitable position. The front end of the tube F 40 opens through the head A at f and receives the air from the room. Arranged at this entrance f is a water-nozzle R, by which water may be sprayed or otherwise admitted into 45 the tube F, and thereby be drawn into the apparatus by the incoming rush of air passing to the fan G.

The air and water passing from the head A descends through the aperture C into the discharge-flue N, which is preferably an upright 50 galvanized-iron tube having a waste-pipe P at the bottom for carrying off the water and an open side O for allowing the humidified air to escape into the room. To prevent the 55 water being thrown out into the room, the edges of this open side of the discharge-flue N are curved, as at n, to form gutters to catch the surplus water and guide it downward to the waste-pipe P. I also prefer that the 60 opening O shall be directed away from the suction-entrance f when both are arranged at the same end of the apparatus, as in Fig. 1, as it insures better circulation within the room.

65 The operation may be described as follows:

The fan being in motion and air circulating, as indicated by the arrows, water is admitted by the nozzle R in the requisite quantity to provide the humidity desired and also the water necessary to produce the washing 70 operation and film over which the air is forced. This admixture of air and moisture is drawn through the tube F with considerable force and driven outward under the centrifugal action of the fan G. This fan is so 75 shaped that it forces the moisture-laden air to flow backward through the annular space between the tube F and shell D with great rotary and centrifugal action, creating, in effect, spiral currents. By this means the water, 80 owing to its greater specific gravity, is caused to spread over the interior surface of the shell D in a thin film, and under the rotary and forward movement of the air said water film is caused to gradually travel forward to 85 toward the head A. In this manner the air is caused to move over a surface of water and press upon it with considerable force, and thereby take up the proper degree of moisture in the shortest period of time to secure 90 the desired humidity. The centrifugal action of the air in its rotary motion continues to assist in holding the water against the interior surface of the shell and to keep it from settling to the bottom thereof. It thus 95 maintains the water-film in the most effective condition and causes it to gradually travel toward the discharge end. When the air and water enter the head A, the rotary action continues until they escape into the discharge-flue N, down the side walls of which the water flows to the waste-pipe P. The air is driven laterally through the aperture O into the room. The degree of humidity of 100 the air so treated may be determined by the use of any well-known type of hygrometer arranged close to the apparatus. The admixture of the water and air in the first instance, coupled with the frictional treatment between the two after leaving the fan, insures 105 the thorough washing and cleansing of the air and clears it of all floating particles or deleterious matters. Any desired length 110 may be given to the tube F and shell D found desirable for any special work, and while it is 115 convenient to inclose the tube F within the shell D to shorten the apparatus as a whole this is not at all necessary, as will be understood by examining Fig. 5. In this figure 120 the tube F' and shell D' are arranged end to end and the fan G' is arranged at the junction of the two parts. In this case the spraying-nozzle R' and the discharge-flue N' are arranged at the most distant ends of the apparatus.

125 It is evident that I may modify the general arrangement and details of the apparatus in many ways without departing from the spirit of the invention.

Having now described my invention, what 130

I claim as new, and desire to secure by Letters Patent, is—

1. In an apparatus for humidifying and cleansing air, the combination of a fixed horizontal cylinder having its interior surface circumferentially unobstructed, a discharge from one end of the cylinder to collect and cause the water to flow away by gravity, a rotatable centrifugal fan arranged at the other end of the cylinder to create a centrifugal action on the air and induce it to move outward in a direction toward the interior surface of the cylinder and cause it to assume a helical motion thereon, means for admitting air to the central portion of the fan, and a water-nozzle for projecting water to the central part of the fan, whereby the fan acts as the sole means for causing both the air and water to travel together through the cylinder in the same direction and assume a rotary motion having a centrifugal action upon the interior surface of the said cylinder and by which the air spreads the water upon the interior surface of the cylinder and then travels over it.
2. In an apparatus for humidifying and cleansing air, the combination of a fixed horizontal cylinder having its interior surface circumferentially unobstructed, a vertical discharge-flue extending downward from one end of the cylinder and having a vertical slot or opening in its side to permit the water to flow away by gravity and the air to escape through the slot or opening, a rotatable centrifugal fan arranged at the other end of the cylinder to create a centrifugal action on the air and induce it to move outward in a direction toward the interior surface of the cylinder and assume a helical motion thereon, and means for admitting air and water to the central portion of the fan, whereby the fan acts as the sole means for causing both the air and water to travel together through the cylinder in the one direction and assume a rotary helical motion having a centrifugal action upon the interior surface of the said cylinder in the opposite direction and by which the air spreads the water upon the interior surface of the cylinder and then travels over it.
3. In an apparatus for humidifying and cleansing air, the combination of two fixed horizontal tubular parts of different diameters the larger having its interior surface circumferentially unobstructed, a centrifugal fan revolving on a horizontal axis arranged at the juncture of the tubular part and for sucking air and water through the smaller of the tubular parts and forcing them through the other or larger part with a helical motion and centrifugal action, and means for spraying water into the smaller tubular part and into the central part of the fan, whereby the water with the air enters immediately at the central part of the fan, and are both made to travel in the same direction through the ap-

paratus and given a helical motion together over the inner surface of the larger tubular part.

4. In an apparatus for humidifying and cleansing air, a tubular part closed at one end, and having an unobstructed internal surface, in combination with a centrifugal fan arranged within and adjacent to the closed end of the tubular part for creating a suction for drawing the air through the central part of the tubular part in one direction and then forcing it outward and in a reverse direction adjacent to the interior tubular surface of the tubular part, and a nozzle to admit a fluid to the air passing to the fan and by which it is conveyed positively to the fan and then forced outward and backward upon the interior surface of the tubular part, whereby the fluid is caused to coat the interior surface of the tubular part in a thin film and the air is caused to assume a helical motion over the film of fluid to cause it to be thoroughly cleansed and humidified.

5. In an apparatus for humidifying and cleansing air, the combination of two pipes one encircling the other, means to admit water to the inner pipe, a discharge-flue from the end of the outer pipe, and a centrifugal fan arranged at the inner end of both pipes for sucking the air and water through the inner pipe and causing it to flow backward through the outer pipe with a rotary motion.

6. In an apparatus for humidifying and cleansing air, the combination of two pipes one encircling the other, means to admit water to the inner pipe, a discharge-flue from the end of the outer pipe consisting of a vertical pipe structure open at one side for the air and having a drain for the water at the bottom, and a centrifugal fan arranged at one end of both pipes for sucking the air and water through the inner pipe and causing it to flow backward through the outer pipe with a rotary motion.

7. In an apparatus for humidifying and cleansing air, the combination of two pipes one encircling the other, means to admit water to the inner pipe, a discharge-flue from the end of the outer pipe consisting of a vertical pipe structure open at one side for the air and having a drain for the water at the bottom and in which the edges bounding the opening are formed with inward gutters, and a centrifugal fan arranged at one end of both pipes for sucking the air and water through the inner pipe and causing it to flow backward through the outer pipe with a rotary motion.

In testimony of which invention I have hereunto set my hand.

JOHN WILLIAM FRIES.
